UNITED STATES PATENT OFFICE.

JOHN T. WEITBREC, OF DENVER, COLORADO.

PRESSURE-CONTROLLED REGULATOR.

No. 910,033.

Specification of Letters Patent.

Patented Jan. 19, 1909.

Application filed June 27, 1907. Serial No. 381,118.

To all whom it may concern:

Be it known that I, JOHN T. WEITBREC, a citizen of the United States, residing at Denver, in the county of Denver and State of Colorado, have invented certain new and useful Improvements in Pressure-Controlled Regulators; and I do declare the following to be a full, clear, and exact description of the invention, such as will enable others skilled in the art to which it appertains to make and use the same.

This invention relates to new and useful improvements in pressure controlled regulators for steam boiler furnaces and has for its object the production of a simple and efficiently operating device of this kind which may be readily applied in operative position to a steam boiler furnace and which is adapted to operate to open the damper or dampers and draft doors of the furnace to cause the fire to burn more vigorously should the pressure in the boiler fall below a certain number of pounds; in other words, to keep the pressure in the boiler within certain fixed limits.

In the accompanying drawings, Figure 1 is a front elevation of the invention applied in operative position to a steam boiler furnace; Fig. 1^a is a horizontal section taken on the plane indicated by the dotted lines *a—a* of Fig. 1; Fig. 2 is a vertical section of the regulator detached from position, and, Fig. 3 is an enlarged detail sectional view of one of the release valves employed in connection with the invention.

Referring more particularly to the drawings, which are for illustrative purposes only and are, therefore, not drawn to scale, the numerals 1, 2 and 3 indicate the ash pit doors, the stack and the damper, respectively, of an ordinary steam boiler furnace.

In carrying out the invention, I provide an upright cylinder 4 comprising a barrel 5 having secured to its upper end a head 6 provided with a stuffing box 7 of any well known construction and with two outwardly extending laterally projecting fastening lugs or plates 8 by means of which the upper end of the cylinder may be attached in position to the front of the furnace.

A piston receiving member is screwed to the lower end of the barrel, said member comprising a bottom 10 formed with a centrally disposed flared valve opening 11 and

an upright cylindrical body 12 provided with two outwardly extending laterally projecting fastening lugs 13 by means of which the lower end of the cylinder may be attached in position to the furnace. A piston 14 is arranged in said piston receiving member and is provided with the usual rod or stem 15 which extends through the stuffing box 7 and is screwed to a cross head 16 connected with the inner end of a horizontally disposed operating lever 17 pivotally connected at said end above the cylinder in any suitable manner and having adjustably mounted on its free end a suitable weight 18.

The numeral 19 indicates a valve member comprising an outwardly flared valve 20 adapted to close the valve opening in the bottom of the piston receiving member and a threaded stem 21 which extends through said valve opening and is screwed to the piston 14.

A cylindrical wall 22 depends from the bottom of the valve receiving member, the lower end of said wall being covered or closed in by a screw-threaded cap 23, the space enclosed by said wall constituting a stem chamber 24, the purpose of which will be disclosed.

A main upright cylinder 25 is attached to the front of the furnace adjacent to the cylinder 4 and comprises an upright barrel 26, the upper end of which is covered by a suitable head 27 provided with a suitable stuffing box 28 and with two laterally projecting fastening studs or plates 29 by means of which the upper end of the cylinder may be fastened in position. The lower end of the barrel 26 is covered by a bottom or cap 30, also provided at diametrically opposite points with laterally projecting studs or plates 31 by means of which the lower end of the main cylinder may be secured in position.

A piston 32 is arranged in said barrel 26 and is provided with the usual rod or stem 33 which extends through the stuffing box 28 and is screwed to a cross head 34 formed with a longitudinal slot 35 near its upper edge to receive one arm of a bell crank lever 36 pivoted to the front of the furnace adjacent to said main cylinder. The other or free arm of said lever is connected by means of the horizontally disposed connecting rod 37 to the free end of a turning arm 38 connected in turn with the upper end of a ver-

tically disposed rock shaft 39 provided with reduced end portions as at 40, which fit in corresponding sockets 41 formed in the inner faces of bearings 42 suitably attached to the front of the furnace. An arm 43 is also secured at one end to one of the ash pit doors 1 and at its opposite end to the lower end of the rock shaft 39 for opening said door when the rock shaft is rocked in one direction and for closing the door when said shaft is rocked in the opposite direction. An arm 44 is also secured to said rock shaft 39 at a point above said doors 1 and is connected with the adjacent end of a horizontally disposed connecting rod 45, the opposite end of which is in turn connected with the free end of an arm 46 fixed to the upper end of a second vertically disposed rock shaft 47, the ends of which are also reduced as at 48 to fit in corresponding sockets formed in bearings 49 suitably secured to the front of the furnace. An operating arm 50 is rigidly connected at its upper end with said rock shaft 47 and at its opposite end with the adjacent ash pit door to open or close the latter as the case may be when said shaft is actuated. A chain 51 is arranged between the cross head 34 and one end of the damper operating arm 52 carried by the outer end of a damper bar or rod 53 which extends transversely through the stack and supports the damper 3.

Communication is established between the steam chamber 24 and the upper end of the main cylinder 25 by the steam conducting pipe 55 and between the piston receiving member 12 and the lower end of the main cylinder by a conducting pipe 56. The piston 14 is normally maintained a suitable distance above the bottom of the piston receiving member 12 leaving a space 51 therebetween, and communicating with said space and with the steam chamber of the boiler is a conducting pipe 58.

An outlet pipe 59 communicates with the body of the piston receiving member 12 at a point above said piston 14 when the latter is in its lowermost position, and is provided at its free end with a vertically disposed or depending escape valve 60. A similar valve 61 is also arranged at a suitable point intermediate of the length of the steam pipe 55, the purpose of which will be shown.

As clearly shown in Fig. 3 of the drawings, said valves comprise cylinders 62 formed in their heads with suitable valve openings 63 adapted to be normally closed by corresponding valves 64 having vertically disposed stems 65 adapted to extend in the vertical bores 66 of adjusting plugs 67 screwing in the bottom walls of said cylinders.

Collars 68 freely encircle the lower ends of said stems and bear on the inner ends of the adjustable plugs 67 and arranged between said collars and shoulders 69 formed near the upper ends of the valve stems are coiled

springs 70. Said cylinders 62 are provided near their lower ends with outlet ports 71 in which are secured outlet pipes 72.

Exteriorly threaded rims 73 are formed at the upper ends of the cylinders whereby they may be screwed in position.

In practice, when the pressure of the steam in the boiler is not sufficient to raise the piston 14, the steam passes through the pipe 58, through the space 57 between said piston and the bottom of the piston receiving member and through the valve opening in the bottom of the piston receiving member into the steam chamber 24 from which it is conducted to the upper end of the main cylinder 25 by the conducting pipe 55. During the passage of the steam from the boiler to the main cylinder, the valve 64 of release valve 61 is held in its seat against the pressure exerted thereon by the steam by its spring 70. After the pressure of the steam in the boiler is sufficiently great to raise the weighted piston 14, the valve 20 of valve member 19 closes the valve opening in the bottom of the piston receiving member 90 and changes the course of the stream through the pipe 56 under the piston 32, the pressure of the steam exerted upon the piston raising the same, and the piston being connected by its stem 33 with the bell crank lever 36 95 actuates the latter, which in turn, through the medium of the connections heretofore described, operates to close the ash pit doors and stack damper.

The ash pit doors and stack damper having been closed, the fire in the furnace gradually burns with less intensity until the steam pressure falls to a sufficient extent to permit the weighted piston 14 to return to initial position, said piston in doing so again changing the course of the steam through the pipe 55 to the main cylinder above the piston 32.

As the piston 32 is raised in the main cylinder the steam or pressure fluid in the pipe 55 is compressed to a sufficient extent to operate the release valve 61 which permits the escape of the exhaust fluid, and said piston, in descending compresses the fluid between it and the release valve 61 to a sufficient extent to operate the latter.

Petcocks 75 are arranged, one near the lower end of the main cylinder and the other in said cap 23 to drain the cylinders. A plug 76 also screws in the cap 23 and is adapted to be unscrewed from position to permit the valve member 19 to be adjusted to increase or diminish the space through which the same is required to travel in order to close the valve opening 11 in the bottom 125 of the piston receiving member 12.

The different parts constituting the invention may be made of any suitable material or materials found most advantageous or desirable in the construction of the invention. 130

The regulator may be so arranged as to operate the stack damper alone or the ash pit doors without the stack damper, but preferably operates both the stack damper and the ash pit doors.

It will be obvious from the construction disclosed that the pressure in the boiler or other apparatus to which the regulator is attached may be kept within certain predetermined limits without the presence of an engineer or attendant.

Various changes in the construction and operation of the invention may be resorted to without departing from the spirit or sacrificing any of the advantages of the invention.

Having thus described my invention, what I claim as new is:—

1. In combination with the ash pit doors and stack damper of a furnace, a main upright cylinder sustained by the furnace, a piston having a stem, movable therein, a second upright cylinder arranged near the main cylinder, a weighted piston movable therein, adjusting means for regulating the movement of the weighted piston, conducting pipes for conducting a pressure fluid under the weighted piston and above the first mentioned piston, a release valve arranged in the conducting pipe between the cylinders, a conducting pipe for conducting the fluid under the first mentioned piston with a predetermined movement of the weighted piston, a discharge pipe communicating with the second mentioned cylinder at a point below the weighted piston, when in its normal position and a second release valve connected with said pipe.

2. In combination with a furnace having ash pit doors and a stack damper, a main upright cylinder sustained thereby, a piston having a stem movable therein, a second cylinder arranged near the main cylinder, a weighted piston movable therein, means for regulating the movement of the weighted piston, a conducting pipe adapted for communicating with the steam chamber of the boiler and the second mentioned cylinder at a point under the weighted piston for conducting a pressure fluid under the latter, means for conducting the fluid from said last mentioned cylinder to the upper end of the main cylinder, means for changing the

course of the fluid under the first mentioned piston with a predetermined movement of the weighted piston, a bell crank pivoted to the furnace and loosely connected at one end with the stem of the first mentioned piston, a vertically-disposed rock shaft sustained by the furnace, near one of the ash pit doors, a second rock shaft sustained near the other of such doors, means for connecting said doors with the rock shafts to cause them to swing in open or closed position by actuating the rock shafts, connections between the rock shafts, and a connection between the outer arm of the bell crank and the first mentioned rock shaft.

3. In combination with a furnace having ash pit doors and a stack damper, a main upright cylinder sustained thereby, a second cylinder arranged near the main cylinder, a piston having a stem movable in the main cylinder, a piston receiving member arranged at the lower end of the second named cylinder, the bottom wall of said member being formed with a valve opening, a piston movable in the piston receiving member, a valve carried by said last mentioned piston and adapted to close said valve opening, a cylindrical wall depending from the bottom of the piston receiving member, a cap covering the outer end of said wall, a conducting pipe for establishing communication between the steam chamber of the boiler and the piston receiving member for conducting a pressure fluid under the weighted piston, a conducting pipe communicating with the cylindrical wall and upper end of the main cylinder for conducting the fluid above the first mentioned piston, conducting means for changing the course of the fluid under the first mentioned piston, with a predetermined movement of the weighted piston, means for permitting the discharge of the exhaust fluid, and connections for connecting the stem of the first mentioned piston with the ash pit doors and stack damper.

In testimony whereof I have hereunto set my hand in the presence of two subscribing witnesses.

JOHN T. WEITBREC.
